Buck et al., "Electrical Connector", U.S. Appl. No. 29/721,751, filed Jan. 23, 2020.

Primary Examiner — Shawn T Gingrich

(74) *Attorney, Agent, or Firm* — Keating & Bennett, LLP

(57) **CLAIM**

The ornamental design for an electrical connector, as shown and described.

DESCRIPTION

FIG. 1 is a top, front, and right side perspective view of a an electrical connector showing our new design;

FIG. 2 is a top, front, and left side perspective view thereof;

FIG. 3 is a top, front, and left side perspective view thereof;

FIG. 4 is bottom, front, and right side perspective view thereof;

FIG. 5 is a top view thereof;

FIG. 6 is a bottom view thereof;

FIG. 7 is a front view thereof;

FIG. 8 is a back view thereof;

FIG. 9 is a left side view thereof; and,

FIG. 10 is a right side view thereof.

The broken lines in the drawing views are included to show portions of the electrical connector that form no part of the claimed design.

1 Claim, 10 Drawing Sheets
